UNITED STATES PATENT OFFICE.

GEORGE A. LAMBERT, OF ANDERSON, INDIANA, ASSIGNOR TO THE BUCKEYE MANUFACTURING COMPANY, OF SAME PLACE.

DESIGN FOR A NECK-YOKE CENTER.

SPECIFICATION forming part of Design No. 29,704, dated November 22, 1898.

Application filed October 22, 1898. Serial No. 694,342. Term of patent 14 years.

To all whom it may concern:

Be it known that I, GEORGE A. LAMBERT, a citizen of the United States, residing at Anderson, in the county of Madison and State of Indiana, have invented and produced a certain new and useful Design for a Neck-Yoke Center, of which the following is a specification, reference being had to the accompanying drawings.

- In the drawings, Figure 1 is a perspective view of my design; Fig. 2, an edge elevation, and Fig. 3 a plan view.

The design consists of the flat pole-piece *a*, having the circular pole-opening *b* formed in it and having one end, as at *c*, rounded to conform to the circular pole-opening and having its other end, as at *d*, enlarged beyond a true circle. Upon the opposite sides of the portion *d* are two enlargements *e*, having their

inner edges rounded off and curved to conform somewhat to the opening *b*, as at *f*. Projecting from the edges of the enlargements *e* farthest from the pole-opening and extending beyond the edge of the pole-piece are circular enlargements *g*, these enlargements having concentric circular openings *h* formed through them and being separated from each other by a space or opening *i*.

I claim—

The design for a neck-yoke center substantially as herein shown and described.

In testimony whereof I hereunto affix my signature, in the presence of two witnesses, this 11th day of October, 1898.

GEORGE A. LAMBERT.
